CENTRALIZED RADIO SYSTEM

Alva R. Hopkins, Merchantville, N. J., assignor to
Radio Corporation of America, a corporation
of Delaware

Application August 13, 1935, Serial No. 35,903

3 Claims. (Cl. 179—1)

An object of this invention is to provide a centralized radio system for the economical distribution of radio programs through several rooms in a dwelling, hotel, school or other building and in which a station selector unit is located in each room by means of which any desired station may be received and caused to operate the loudspeaker located in the room.

A further object is to provide an additional control station located at some central point in the building and which is so connected to the several loudspeakers and the different program channels that the operator thereof may silence the loudspeaker in any room or connect it to any program channel he prefers.

A still further object of the invention is to provide an audio sound source such as a microphone or phonograph pickup device at the central control station which may be connected to the audio frequency amplifier of one of the station receivers so that the operator may make announcements to any desired room or number of rooms. Other objects of the invention will become apparent to those skilled in the art as the description thereof proceeds. For a better understanding of the invention, however, reference is made to the accompanying drawing in which the single figure shows diagrammatically a centralized radio system arranged according to my invention.

In the drawing each of the channel racks 10 and 11 comprises a tunable radio receiver, audio frequency amplifier and loudspeaker, a more detailed description of these units being given in the patent to A. F. Van Dyck, 1,968,546 granted July 31, 1934. These units are preferably located at a central location such as in the principal's office of a school. It will also be understood that the radio receiver of each unit is preferably tuned to receive a different broadcasting station so that the channel A' carries the modulation frequency of station A and channel B' that of a station B. Located in a room remote from the channel racks such as in a classroom designated by the dotted lines R is a channel selector device 12 comprising a switch blade 13 contacts 1, 2 and a third contact marked "Off". As shown contact 1 is connected to channel A' and contact 2 to B' while switch 13 is connected to a terminal R. C. of a master control panel 14 to be described. It will also be understood that the selector device 12 may include a volume control unit as described in the Van Dyck patent above noted. A sound reproducer such as a loud speaker 15 is preferably also

mounted in the room R and connected as shown to a movable switch blade 16 of the unit 14.

Located in another room as designated by line R' are a selector device 12 and speaker 15 connected and arranged similarly to those in room R. Located at the central location preferably near the channel racks 10, 11 is the master control panel 14 which is provided with a number of similar switch control units S. Each unit is provided with a movable switch blade 16, a contact marked "Off" and also a contact for each channel of the system, the contacts 1' being connected to channel A' and contacts 2' to channel B'. It will be understood that a control unit S will usually be provided for each speaker to be controlled and as many switch positions on each as there are radio channels provided.

In the operation of the system the principal will usually leave the switches 16 on contacts R. C. as shown. The instructor may then throw his speaker 15 out of circuit by placing switch 13 in the position shown or he may connect it to channel A' by moving it to position 1 or to channel B' by moving it to position 2. It will be seen that with the switch in position 1 the principal may silence the corresponding speaker by moving the corresponding switch 16 to the "off" contact or he may connect it to channel B' by moving switch 16 to position 2'. It will thus be seen that the several speakers are under the control of the principal or other central station supervisor at all times irrespective of the position to which the switches 13 may be adjusted and he may connect all speakers to the same or to different channels according to his desire. While the return lines from the speakers to the low potential side of the audio output terminals 18 are shown as ground, it will be understood that two wire connections may be used instead.

Input jack terminals 19 of the audio frequency amplifier of one or more of the channels may be connected when the station is detuned to the output terminals of a microphone 20 or a phonograph pickup and then by connecting one or more speakers to the corresponding channel, the principal may address the occupants of one or more rooms by suitably setting one or more of the switches 16. Or if a phonograph pickup is used instead, recorded music may be reproduced in any desired room or rooms as desired.

While only two speakers and control units 12 have been shown, it will be understood that any desired number may be used within the available power output of the audio amplifiers of the re-

ceivers, the number of switch units S being made to correspond.

Having described my invention what I claim as novel and desire to secure by Letters Patent is:

- 5 1. In a centralized radio system, the combination of a plurality of audio frequency current sources, a plurality of sound reproducers located at points remote from said sources, connections between said reproducers and sources, at least one 10 of said connections including a switching device located adjacent said reproducer and arranged to connect it to either of said sources and a second switching device located at a point remote from said reproducer and arranged to connect it to either of said sources irrespective of the position 15 of said first named switching device and a line connecting said switching devices in series.
2. In a centralized radio system, the combination of a panel comprising a radio receiver having audio frequency output terminals, means for selectively connecting a microphone to said terminals, a sound reproducer located at a point remote from said receiver, a switch arranged to connect

said reproducer to said output terminals and a second switch located adjacent said microphone arranged to connect said microphone and output terminals to said speaker irrespective of whether the first named switch is open or closed and a line connecting said switches in series. 5

3. In a centralized radio system, the combination of a radio receiver having output terminals, an amplifier panel having output terminals one of each of said pairs of output terminals being grounded, a microphone connected to said amplifier panel, a first and a second loud speaker located at points remote from said panels one terminal of each of said speakers being grounded, a switching device arranged to connect both said speakers to said receiver output terminals, and a second switching device located adjacent said microphone arranged to disconnect said first speaker from said receiver output terminals and connect it to the output terminals of said amplifier. 10 15 20
